Primary Examiner — Barbara Fox

Assistant Examiner — Holly E Thurman

(57) **CLAIM**

The ornamental design for a camera, as shown and described.

DESCRIPTION

Reproduction 1.1 is a front, right perspective view of a camera showing the new design in a first embodiment.

Reproduction 1.2 is a back, left perspective view thereof.

Reproduction 1.3 is a left side view thereof.

Reproduction 1.4 is a back view thereof.

Reproduction 1.5 is a front view thereof.

Reproduction 1.6 is a back, right side perspective view thereof.

Reproduction 1.7 is a front, left side perspective view thereof.

Reproduction 2.1 is a front, right perspective view of the camera showing the new design in a second embodiment.

Reproduction 2.2 is a left side view thereof.

Reproduction 2.3 is a front view thereof.

Reproduction 2.4 is a back, right side perspective view thereof.

Reproduction 2.5 is a front, left side perspective view thereof.

The broken lines in the drawings are for illustrative purposes only and form no part of the claimed design.

1 Claim, 12 Drawing Sheets
